TOOL HANDLE FASTENING

Dorse M. Waters, Belmont, N. Y.

Application June 6, 1950, Serial No. 166,477

2 Claims. (Cl. 30—342)

1

This invention relates to knives and more particularly to large knives used principally by woodsmen and relates specifically to the handle construction of such knives, it of course being understood that the novel handle construction is capable of use with any kind of knife or other tool handle.

The main object of the invention is to provide a knife with the usual blade, the blade terminating in a handle supporting tang, said tang having stamped out from the metal thereof at its end a toothed locking pin having a plurality of formed teeth, which teeth engage the teeth and the shoulders of corresponding teeth formed within the tang slot when the toothed wedge is driven home to lock the handle leathers upon the tang.

A further object of the invention consists in welding or otherwise suitably attaching the locking wedge to a solid metal cam member, whereby the wedge can be quickly and easily driven into its locking position with the tang by simply striking the cap with a hammer or the like.

Other objects and advantages will become apparent when considered in the light of the following description and accompanying drawings in which:

Fig. 1 is a side elevational view of the assembled knife;

Fig. 2 is a view in side elevation with the handle leathers and knife guard in section and showing in detail the locking wedge in its assembled relation;

Fig. 3 is a perspective view of the handle cap and locking wedge; and

Fig. 4 is a detailed view of the end of the tang showing the locking wedge removed.

Referring specifically to the drawings in which like numerals have been used to indicate similar parts throughout the various views, the knife blade is shown at 6, said blade having the usual cutting edge 7 and back 8. The blade 6 is further provided at its rear end with a finger guard 9 as an integral part of the blade, which guard prevents the fingers and hand of the user from slipping into contact with the cutting edge of the blade when in use.

The blade 6 terminates in its inner end with a tang 10 which is somewhat reduced in size as respects the blade, the tang being rectangular in shape. A multiplicity of oval shaped handle forming leather discs 11 having rectangular slots therein, which slots are adapted to be of the same size as the tang whereby the same can be slid onto the handle tang 10, the intermediate discs being of larger circumference than the adjacent front

and rear discs, the discs thus gradually reducing in size from the center of the handle to the rear and front thereof to form a hand grip which will follow the contour of the user's hand.

5 The tang 10 along its center portion and adjacent its outer end has stamped out therefrom as by a stamping die or the like a wedge shaped locking pin 12, said pin during the stamping operation being cut to provide along its opposite sides or edges a plurality of ridge engaging teeth 13. The tang 10 from which the locking pin 12 is die cut is left with a longitudinal slot 14 and inwardly extending teeth portions 15 on opposite sides of the slot, the slot 14 further terminating at its innermost end in a circular opening 16 which may have been previously cut therefrom, and it will be noted that by the removal of the die cut locking lug 12 from the same material as that of the tang 10 that the side members 17 and 18 of the tang contain a certain natural resiliency which tends to urge the prongs 17 and 18 together or at least toward each other.

20 Each tooth 13 is provided along its respective sides with outwardly tapering portions 19 which are adapted to engage the complementary tapering surfaces 20 of the respective teeth 15.

25 The knife is provided with a solid metal stainless steel cap 21 of oval form to the central inner surface of which is welded or otherwise securely fixed the outer end or base of the locking pin 12.

30 In the assembly of the knife handle, the tang portion 10 is first die cut to remove the toothed locking pin 12. Thereafter, the pin 12 is welded or fixed to the cap member 21. After this has been accomplished, the plurality of oval shaped handle leathers 11 are progressively fed onto the tang and of course in the proper relation to give shape to the handle. After the handle leathers have been pushed onto the handle tang it is only necessary to take the toothed pin 12 and its cap and upon placing the leading end of the pin in alignment with the slot 14, and thereafter striking the head 21 with a hammer or mallet to drive the toothed pin home, that is into the tang slot, 35 whereupon the teeth 13 interengage with the teeth 15 of the tang which securely locks the cap 21 to the tang and in addition the inner face of the cap 21 engages the outermost handle leather and forces and holds the same in tightly abutting relation.

40 It has been found that after the locking pin has once been driven home that the same will last the life of the article and in order to remove the same it would be necessary to cut through a sufficient number of the leathers to allow sidewise

removal of the toothed pin. Thus, I have provided a very efficient, time saving and low cost means of locking the various handle leathers to a knife handle. It will of course be realized that the invention could readily be adapted for use not only with a knife handle, but with many tool handles, such as hammers, chisels and the like, and the invention as disclosed is in the preferred form but is capable of considerable variation and modification within the scope of the following claims.

I claim:

1. A knife comprising in combination, a blade provided with a rearwardly extending tang, a plurality of handle forming discs mounted upon and extending the full length of the tang, a handle cap having a toothed locking pin secured thereto, the tang having a toothed slot therein, the teeth of the locking pin and the teeth of the toothed slot in locked engagement when the locking pin is driven into the slot, the inner surface of the handle cap contacting the outermost discs to compress the same and hold the discs upon the tang.

2. A knife comprising in the combination, a blade provided with a rearwardly extending tang, said tang being substantially rectangular in shape and having a slot extending inwardly of

its end, said slot having a plurality of oppositely disposed teeth formed on the inner surface thereof, a plurality of handle forming leather discs mounted upon the tang, an end cap for the handle, and a toothed locking pin secured to the cap and adapted to be driven into the tang slot whereby the respective teeth of the tang engage the teeth of the locking pin to prevent its withdrawal, the cap member engaging the outmost leather disc and holding the plurality of discs upon the tang.
